UNITED STATES PATENT OFFICE.

ARTHUR EHREHOLD SCHULZ, OF CHICAGO, ILLINOIS, ASSIGNOR TO WESTERN ELECTRIC COMPANY, INCORPORATED, OF NEW YORK, N. Y., A CORPORATION OF NEW YORK.

STRAND HOLDER.

Application filed June 21, 1924. Serial No. 721,381.

This invention relates to strand holders and more particularly to tape pad holders.

An object of the invention is to provide a strand holder which will permit the ready removal of a tape pad or the like therefrom in a minimum amount of time.

Another object of the invention is to provide an improved strand holder from which a tape pad may be readily removed without 10 distorting the tape or causing it to unwind.

In accordance with the general features of the invention there is provided a strand holder comprising a head fixed to a winding arbor, a second head and a hub attached thereto, the head and hub being attachable to and detachable from the winding arbor as a unit, the hub comprising a split clock spring band, the ends of which are adapted to be spread apart or drawn together by 20 means of two levers, secured thereto, which are actuated by a cam, latch means being provided for holding the removable head and hub on the winding arbor when applied thereto.

Other objects and advantages of the invention will more fully appear from the following detailed description taken in connection with the accompanying drawings which illustrate one embodiment thereof, and 30 in which—

Fig. 1 is an end elevation of the detachable portion of the strand holder;

Fig. 2 is a side elevation of the strand holder partly in section;

Fig. 3 is a vertical sectional view of the strand holder shown in Fig. 2 taken on the line 3—3 thereof showing the hub contracted;

Fig. 4 is a vertical sectional view taken on 40 the line 4—4 of Fig. 1, looking in the direction indicated by the arrows, showing the complete strand holder applied to an arbor, and

Fig. 5 is a detail sectional view taken on 45 line 5—5 of Fig. 2 showing the construction of the latch mechanism.

Referring now to the drawings in detail in which like reference numerals designate similar parts throughout the several views, 50 10 denotes a winding arbor to which is secured a head 11. Surrounding the arbor 10 is a similar head 12 which is spaced from the head 11 by a hub, denoted generally by reference character 13. The hub 13 comprises a

split flexible band 14, (Fig. 1) the ends of which are adapted to be spread apart or drawn together by levers 15 and 16 respectively, secured thereto.

The lever 15 comprises an arm 17 (Fig. 2) extending from a hub 18 (Fig. 2) at one end, the other end of the arm being integral with a cross-piece 19 which is secured to one end of the band 14 by screws 9. Formed on the side of the hub 18 opposite that side to which the arm 17 is secured is 65 an arm 20 (Fig. 2) which has formed on its end an integral cross-piece 21. The lever 16 comprises two arms 22 and 23 (Fig. 2) formed on hubs 24 and 25, respectively. The ends of the arms 22 and 23 are joined together by a cross-piece 26 which is secured to the other end of the split band 14 by screws 27. Formed on the side of the hubs 24 and 25 respectively, opposite to that side to which the arms 22 and 23 are secured, 70 are two arms 28 (Figs. 1 and 2) and 29. The ends of the arms 28 and 29 are joined together by a cross-piece 30 which is directly opposite the cross-piece 21 of lever 15. The hub 18 is positioned intermediate the hubs 80 24 and 25 on a sleeve 31 which surrounds the arbor 10. The hubs being kept in place on the sleeve 31 by a ring or washer 32 which is secured to the sleeve 31 by a screw 33.

The sleeve 31 is secured to the head 12 by 85 screws 34 and 35 which are threaded therethrough into pins 36 and 37, respectively. The pins 36 and 37 are tapered and their ends are adapted to engage holes 38 and 39 in the head 11, (Fig. 2) these pins keeping 90 the heads in a fixed position with respect to each other. The cross-pieces 21 and 30 of levers 15 and 16 respectively, are adapted to be spread apart by a cam 40 secured to a cam lever 41 which is journaled in the sleeve 95 31. Secured to the arm 17 adjacent the cross-piece 19 is a spring 42 whose other end is secured to the cross-piece 26 of the lever 16 intermediate the arms 22 and 23 (Fig. 2) thereof, the spring functioning to draw the 100 two ends of the band 14 together. Formed in the sleeve 31 (Fig. 5) is a slit or hole 43 in which is located a latch 44, which is pivotally mounted on a screw 45. A knurled end 46 of the latch 44 is pushed outwardly by a spring 47 located in the sleeve 31 and end 48 of the latch 44 is adapted to be inserted into a groove 49 in the arbor 10. By 105

pressing on the end 46 of the latch 44, the end 48 is brought out of engagement with the arbor thereby permitting the removal of the hub 13 and head 12 therefrom.

5 It is evident that by actuating the lever 41 the band 14 may be contracted or expanded. Normally when material is being wound on the hub 13 by rotating the arbor 10, the band 14 will be expanded, but upon 10 removal of the hub 13 and the head 12 from the arbor 10 to permit the removal of the material therefrom, the lever 41 would be actuated to contract the band 14 thereby 15 permitting the material previously wound to be very easily and readily removed.

The strand holder herein disclosed is particularly advantageous in taking up material in tape or other similar forms, inasmuch as the material wound thereon may be readily removed in a minimum amount of time.

20 It is to be understood that the above described strand holder may be modified in many respects without departing from the spirit and scope of the invention and that 25 the invention is to be limited and restricted only by the appended claims.

What is claimed is:

1. In a strand holder, a winding arbor, a head attached thereto, a second head, and 30 a hub intermediate said heads and secured to said second head, the hub and the second head being attachable to and detachable from the winding arbor as a unit, the hub comprising a split band, a pair of levers, and means for actuating the levers to contract or expand the band.

2. In a strand holder, a winding arbor, a head attached thereto, a second head, and 40 a hub intermediate said heads and secured to said second head, the hub and the second head being attachable to and detachable from the winding arbor as a unit, the hub

comprising a split band, and resilient means for drawing the ends of the band together.

3. In a strand holder, a winding arbor, 45 a head attached thereto, a second head, and a hub intermediate said heads and secured to said second head, the hub and the second head being attachable to and detachable from the winding arbor as a unit, the hub 50 comprising a split band, a pair of levers, a cam for actuating the pair of levers to expand the band, and resilient means for drawing the ends of the band together.

4. In a strand holder, a winding arbor, 55 a head attached thereto, a second head, a hub intermediate said heads and secured to said second head, the hub and the second head being attachable to and detachable from the winding arbor as a unit, and latch 60 means for securing the removable head and hub on the winding arbor when applied thereto, the hub comprising a split band, a pair of levers, a cam for actuating the pair of levers to expand the band, and resilient 65 means for drawing the ends of the band together.

5. In a strand holder, a winding arbor, a head attached thereto, a second head, a hub intermediate said heads and secured to 70 said second head, the hub and the second head being attachable to and detachable from the winding arbor as a unit, latch means for securing the removable head and hub on the winding arbor when applied thereto, and means for positioning the detachable head with relation to the fixed head, the hub comprising a split band, a pair of levers, a cam for actuating the pair of levers to expand the band, and resilient means for 75 drawing the ends of the band together.

In witness whereof, I hereunto subscribe my name this 7th day of June A. D., 1924.

ARTHUR EHRHOLD SCHULZ.
